SLIME TABLE

Charles B. Ulrich, Jamestown, N. Y.

Application May 13, 1931, Serial No. 537,070

26 Claims. (Cl. 209—14)

My invention relates to an improved construction of slime table for collecting precious metal in finely sub-divided condition, occurring, for example, in ore concentrates, in connection with 5 milling ore containing such precious metals, for example gold, silver and the platinum family.

In the past, it has been usual, particularly in connection with placer mining, to first effect a rough separation of the metals from the bulk of 10 the crushed ore, after which the fine particles of the precious metals, carried by the mass of the refuse and the water employed in the operations, have been permitted to settle and separate from the mass of the refuse, after which the fine particles 15 of the precious metals have been brought into contact with mercury to recover them by amalgamation with the mercury. I find that with the use of slime tables and devices for bringing the fine particles of precious metals into contact 20 with the mercury as heretofore employed, particularly where the particles of the precious metals are in very finely sub-divided condition, the recovery has been inefficient due to the difficulty of effecting thorough amalgamation, by bringing 25 the mercury into contact with all of the metallic particles. By my present invention, I provide a construction of slime table which not only brings the finely divided particles into contact with the mercury employed in the amalgamation, but 30 in addition, my construction provides for moving the mercury and the metallic particles and material treated upon each other, with the effect that the metallic particles and the mercury are thoroughly mixed, bringing practically all of the metallic particles into contact with the mercury, so 35 that the amalgamation is highly efficient. This applies of course, only to metals that will amalgamate with mercury. As below described, I provide for collecting the finely divided particles of other metals, in another manner.

My invention will best be understood by reference to the accompanying drawings showing a preferred embodiment thereof, in which

Fig. 1 illustrates one form of my slime table in vertical, central, sectional view.

Fig. 2 is a horizontal sectional view to an enlarged scale, of the parts shown in Fig. 1, taken along the line 2—2.

Fig. 3 is a horizontal sectional view of the parts shown in Fig. 1, to an enlarged scale taken along the line 3—3.

Fig. 4 is a sectional view to an enlarged scale, of the parts shown in Fig. 1, taken along the line 4—4.

Fig. 5 is a horizontal, sectional view to an enlarged scale, of the parts shown in Fig. 1, taken along the line 5—5.

Fig. 6 is a plan view to an enlarged scale, of a part of the table shown in Fig. 1, taken along the line 6—6.

Fig. 7 is a sectional view to a further enlarged scale, of a part of the construction shown in Fig. 6, taken along the line 7—7.

Fig. 8 is a sectional view of a part of the construction shown in Fig. 6 to a further enlarged scale, taken along the line 8—8.

Fig. 9 shows in plan view, a modified arrangement of slime table and filtering bed,

Fig. 10 is a sectional view of the parts shown in Fig. 9 to an enlarged scale, taken along the line 10—10.

Fig. 11 is a sectional view of the parts shown in Fig. 9 to an enlarged scale, taken along the line 11—11, and

Fig. 12 is a sectional view of a part of the structure shown in Fig. 11 to a further enlarged scale, taken along the line 12—12.

Similar numerals refer to similar parts throughout the several views.

As shown in Fig. 1, my slime table consists of a conical base 10 of any suitable supporting material, for example sheet metal, pressed wood, or other material adapted to the purpose, supporting sections 11 of material for carrying the mercury employed, in a manner described below. The base 10 is reinforced by angle bars as indicated at 12, 13, and 14, and supporting frameworks 15, 15 are secured to the angle bars 13 and 14 and extend downwardly therefrom to engage and be supported by one member 16 of a ball-bearing, the other member 17 of which receives a stationary support as indicated, from piers 18 extending upwardly from the foundation 19 of the device. As a result, the table may rotate about its vertical axis as permitted by other parts of the mechanism described below.

The sections 11 of the table are covered by a relatively fine mesh screen 20, which prevents particles larger than a desired size, engaging the mercury carried by the sections 11.

The table is provided with a central opening 22 surrounding the upper ends of brackets 23 extending upwardly from the piers 18, 18, to support a ring 24 in stationary position, co-axial with the vertical axis of the table. A pipe 25 is mounted in vertical position, or substantially so, and extends through the ring 24, said pipe having an enlarged upper end as shown at 26, to act as an overflow for material supplied to the pipe 25.

The enlarged portion 26 of the pipe 25, is surrounded by an annular shield 27 secured to the upper portion of the pipe by studs 28 as indicated, so that a clearance space is provided between the rim of the enlarged portion 26 and the inner surface of the shield 27. The lower end of the shield 27 is flared inwardly as indicated at 27a, so that any liquid material flowing over the edge of the portion 26 into the shield 27, will drip along a line indicated at 29 towards the upper portion of the table.

The pipe 25 has extending into it, a first hose 30 which may be used to supply the slime to be treated by the device, to the pipe 25. The hose 30 is preferably armored to protect it from mechanical injury and withstand the pressures required to pump the liquid material through the hose. A second hose 31 similar to the hose 30, also extends into the pipe 25, to supply water to the pipe as may be required to float the finer particles of the slime, including the finely subdivided metals, over the rim of the portion 26 of the pipe 25.

The pipe 25 is supported from the ring 24, as more clearly shown in Fig. 2. As shown in this figure, the pipe 25 has rigidly secured to it, a ring 32 having studs 33, 33 extending oppositely therefrom, which have bearing supports in an intermediate ring 34. The ring 34 is provided with studs 35, 35 extending oppositely from it, midway between the studs 33, 33, and into bearing engagement with the ring 24. In this manner, the weight of the pipe 25 and its contents, is carried by the ring 24 in a manner preventing rotation of the ring and pipe, and yet permitting the axis of the pipe to have a wobbling motion imparted to it. The pipe 25 has secured to it above the ring 32, a hood 36 which prevents any of the liquid material delivered from the rim 26, dropping into or against the parts carried by the ring 24.

Below the ring 24, the pipe 25 is provided with a lower end portion 37 of conical form, the lower end of which extends through a horizontally disposed gear 38 supported by downwardly extending arms 39, 39 from a stud shaft 40 supported in vertical position for turning movement in a pedestal 41 carried by the foundation 19.

As more clearly shown in Fig. 3, the gear 38 is provided with a web 42 having a radial slot 43 therethrough. The web 42 has mounted upon it, by means of a pivot rod or screw 44, a plate 45 provided with a slot 46 extending angularly across the slot 43. The plate 45 is also provided with a second slot 47, which is in the form of an arc about the pivot screw or rod 44. A clamping screw 48 extends through the slot 47 into threaded engagement with the web 42, so that the plate 45 may be clamped in any desired position of adjustment. The slots 43 and 44 are of the same width and this width is substantially the outer diameter of the pipe portion 37 where it extends through the gear 38. The axis of rotation of the gear 38 is substantially co-axial with the vertical axis of the table 10, and in this manner the pipe portion 37 may be caused to describe a circle of desired diameter, depending upon the adjustment of the plate 45 on the web 42, when the gear 38 is rotated, without imparting rotation about its own axis to the pipe 25.

The wobbling motion imparted to the pipe 25 by rotation of the gear 38, serves to spill the overflow from the pipe 25, over the rim 26 successively at different points around the rim, to

the end that the liquid material dropping from the shield 27, is uniformly distributed around the upper portion of the table.

The gear 38 meshes with a pinion 49 carried by a vertical shaft 50, to the lower end of which is secured a first bevel gear 51 meshing with a second bevel gear 52 rigidly secured to a driving shaft 53 which may be operated from any suitable source of power not shown. The upper end of the shaft 50 carries a crank 54 engaging one end of a connecting rod 55, the other end of which engages a stud 56 rigidly secured to a bracket 57 carried by the angle bar 13 of the table. The relation of the crank 54 to the stud 56 is more clearly shown in Fig. 5. As a result of this construction, when the shaft 50 is rotated to wobble the pipe 25, the table 10 is oscillated by the crank 54, and as a result of the gear 38 being much larger than the pinion 49, the table is oscillated at a more rapid rate than the pipe 25 is wobbled.

The lower tapered portion 37 of the pipe 25, is provided with a valve casing 58 provided with a valve member pivotally supported at 59, from which an arm 60 extends outwardly to engage a stud 61 carried by the gear 38, the stud 61 being preferably located on the gear 38 in line with the outer end of the slot 43, as indicated in Fig. 3, and the arm 60 preferably extending from the pipe portion 37, in the same direction. As a result, as more clearly shown in Fig. 4, when the gear 38 rotates in the direction indicated by the arrow, the arm 60 is engaged by the stud 61 and moved on its pivotal support 59, thus opening the valve disk 58a momentarily, and allowing the heavy material collected in the lower portion of the pipe 25, to discharge from the lower end of said pipe, for subsequent treatment, as may be desired. A spring 62 is provided between the arm 60 and a second arm 63 extending from the valve casing 58, to close the valve 58a when the stud 61 passes beyond the end of the arm 60. The arm 60 and the stud 61 may be proportioned in any desired manner, to control the period of opening of the valve member 58a for each engagement of the arm 60 by the stud 61.

The covering material 11 of the table 10, preferably consists of segmental sections, as shown in Fig. 6, which are preferably made of relatively soft rubber. To facilitate handling these sections, it is desirable that they be not of too great extent, and I find it convenient to make these segments of substantially forty-five degrees each, although any other desired number of sections may be employed if preferred. The outer edge 55 of the table 10 is provided with an upwardly extending flange 10a retaining the segments of the covering material 11 in place with their edges tightly pressed against each other as indicated at 11a and 11b. The segments of the covering material 11 have annular grooves 64 in their upper surfaces, said grooves being co-axial with the axis of the table 10, and there being as many of these grooves as can be conveniently arranged in the covering material 11, according to the size of the table 10. The grooves 64 are preferably formed as shown in Fig. 7, the lower or outer wall 64a of each groove being inclined upwardly and towards the axis of the table 10, while the inner or upper wall 64b of each of these grooves is curved so as to widen the groove somewhat outwardly and upwardly, and engage the upper surface of the covering material tangentially. Each of the segments of the cover-

ing material 11 is provided with a plurality of partition walls 65 extending radially of the table, and between adjacent partition walls, each groove contains mercury as indicated at 66. As shown 5 in Fig. 8, each partition wall 65 is preferably formed of thin sheet metal folded upon itself, so that its upper edges may be bent outwardly away from each other as shown at 65a, to constitute outwardly deflecting walls for directing 10 the mercury back into the grooves 64, in the event the oscillation of the table 10 is vigorous enough to throw the mercury upwardly on the partition walls 65.

While it is not intended that pieces of solid 15 material of large size will be delivered to the table from the shield 27, I find it desirable to prevent the coarser solid matter delivered from the shield 27, from reaching the screen 20 and interfering with the treatment by the table of 20 the finer slimes. This I accomplish by mounting a conical shield 76, preferably of sheet metal, above the screen 20, on posts 77 carried by the lower portion of the base 10, which shield 76 is 25 of larger inner diameter than the screen 20, and carries a relatively coarse mesh screen 75 extending over the inner part of the screen 20 and in the path of the drip from the shield 27. The lower edge of the shield 76, preferably extends 30 sufficiently beyond the moving parts of the machine, to deliver the relatively coarse solid material from the machine, for collection or disposition in any desired manner, not shown.

As a result of the construction described, the liquid material delivered from the rim 26 and 35 flange 27a, is distributed around the upper and inner portion of the table 10, carrying with it in finely sub-divided form the precious metals to be recovered; the liquid mixture first engages the screen 75 which removes the relatively coarse 40 solid material; the remaining slime then engages the screen 20 which removes the smaller solid matter which is too coarse to be treated by the table, and the fine slime flows down the upper surface of the material 11, and from one to another of the grooves 64, until the remaining slime reaches the lower edge of the table. As the slime 45 flows slowly down over the surface of the table, it comes successively into engagement with the several portions of mercury 66, and the oscillation of the table serves to agitate the slime and to thoroughly bring its metallic particles into 50 contact with the mercury, which permits much more thorough amalgamation of the precious metals with the mercury, than if the oscillation did not occur. It will be observed that the fine 55 particles of the metals will tend to remain in the grooves 64, on account of being heavier than the remaining slime, and as a result, if the particles of metal are not engaged by the mercury 60 at first, the mercury is repeatedly moved over them by the oscillation of the table, so that substantially all of the precious metals in the slime susceptible of amalgamation, are collected by the 65 mercury and amalgamated with it.

After the mercury has picked up all of the 70 precious metals it can hold effectively, the operation of the table is stopped, the mercury is collected and removed from the table, and distilled to recover the values carried by it. To facilitate 75 cleaning up the table and collecting the mercury, the partitions 65 are made sliding fits in corresponding grooves in the covering material 11, and the partitions are provided with holes 65b through them which, when the partitions are moved somewhat towards the axis of the table 10, reg-

ister with the grooves 64, so that the mercury in any groove may flow from the several segments to a single point in the groove and be readily collected from the groove. Each of the partitions 65 is preferably provided with one or more holes 5 65c through its upper portion, for engagement with a suitable tool for sliding the partition either to register the holes 65b with the grooves 64, or to cover the holes 65b and restrict the mercury action in any groove, to the space between two 10 adjacent partitions 65. I find that for effective operation, the angle of oscillation of the table by the crank 54, should preferably be substantially the same as the angle between successive or adjacent partitions 65, to the end that the mercury 15 in any groove between adjacent partitions may be caused to travel from end to end of that particular part of the groove 64, for each complete movement of the table 10 in a direction to produce the movement just referred to of the mercury. 20

The lower edge of the table 10 has secured thereto a metal trough 67 having a perforated bottom as indicated at 67a, said trough being nearly filled with sponge rubber or other finely subdivided filtering material as indicated at 68. The piers 18 carry brackets 69 extending around the outer edge of the trough 67 and over the same, to support rollers 70 in engagement with the upper surface of the filtering material 68, as a result 30 of which oscillation of the table 10, rolls the filtering material 68 under the rollers 70 so as to press the water contained in the filtering material through it and retain in the filtering material any fine particles of solid material which may 35 find their way into the trough 67 from the lower edge of the table 10. As many rollers 70 may be employed as desired. In this manner the trough 67 collects the remaining solid material in the slime which is not susceptible of amalgamation, 40 for example rare metals of the platinum family when they are present in the slime, and the water flowing over the edge of the trough 67 and through its perforated bottom 67a, may be conveniently 45 collected in a stationary trough 71 supported by brackets 69, from which trough the liquid may be discharged in any desired manner.

The arms 39 of the gear 38 preferably support a pan 72 around the lower end of the conical portion 37 of the pipe 25, to receive the material 50 discharged from said pipe by the opening of the valve member 58a, this pan being provided with an outlet pipe 73 discharging into a fixed trough 74 carried by the pedestal 41, said trough 74 discharging its contents in any convenient manner. 55

In Fig. 9 I illustrate a modified form of my slime table and filter bed construction, in which I show a reciprocable slime table 114 of rectangular form, having its entire surface arranged for treatment 60 of the slime, and a separate reciprocable filter bed 120 for receiving the remaining slime from the table 114. The slime to be treated by the table is fed to it by a trough 117 from undercurrents derived from a sluiceway or sluiceways in placer mining, from settling tanks, or from any other 65 source of slime containing metal particles susceptible of recovery by the treatments of the present invention. After the slime has been treated by the table, it is discharged from the lower end thereof to a trough 118 which is widened at its 70 discharge end as shown at 118a, the widened portion being provided with partitions 119 to distribute the slime over a much greater width than that of the table 114. The discharge end of the trough 118 delivers the slime to the upper portion 75

of a relatively wide filter bed 120. The liquid, and whatever remaining material is carried thereby, after being acted upon by the filter bed 120, is delivered to a discharge trough 121 to be carried to any desired point. The parts described are supported on a base 122. The slime table 114 is provided with lugs 123 pivotally connected with connecting rods 124 engaged by cranks 125 carried by a shaft 126 mounted in bearings 127 supported by the base 122. The shaft 126 carries a gear 128 by which the shaft may be rotated from any suitable source of power and at any desired rate of operation. The filter bed 120 is provided with lugs 129 pivotally connected with connecting rods 130 engaging cranks 131 carried by a shaft 132 mounted in bearings 133 carried by the base 122. The shaft 132 has mounted thereon a gear 134 by which the shaft may be rotated at any desired speed from any suitable source of power not shown.

The entire upper surface of the slime table 114 is provided with a covering 115 similar to the covering 11 above described. The covering 115 is provided with grooves extending laterally thereof, similar to the grooves 64 above described, excepting that they are straight instead of annular. The grooves in the covering 115 are crossed by partition walls 116 of the construction described above for the partition walls 65, extending longitudinally of the table 114 and sub-dividing the grooves in the covering 115 into short sections, each of which contains mercury, as and for the purposes above described in connection with the grooves 65.

The slime table 114 is supported by rods 135 extending upwardly therefrom in pairs, each pair of rods, as more clearly shown in Fig. 10, extending through the ends of a yoke 136 resting at its mid portion upon a ball or roller bearing 137 carried by a shaft 138 at a substantial distance above the slime table 114 and extending longitudinally of the slime table. The shaft 138 is supported by frames 139 spanning the table 114 and carried by the base 122. The upper ends of the rods 135 are preferably provided with nuts 135a for securing desired adjustments of the yoke 136 relatively to the slime table 114. With this construction, when the shaft 126 is rotated, the slime table 114 is oscillated on the bearings 137, and since these bearings are a substantial distance above the slime table and the throw of the cranks 125 is preferably small, the amount of power required to oscillate the table is relatively small since the speed of oscillation is never great, ranging preferably from 100 to 150 oscillations per minute. The proportions of the parts should be such, relatively to the rate of oscillation, that the rate of oscillation imparted to the table by rotation of the shaft 126, will be different from the natural rate of oscillation of the table 114 about the axis of the shaft 138, acting as a pendulum, to the end that the oscillation of the table may produce movement of the mercury in the grooves of the covering 115 of the table, this movement of the mercury being preferably from end to end of the parts of the grooves in any case, in which the mercury is confined by the partitions 116, for each oscillation of the table 114. The filter bed 120 is preferably supported by rods 140 for oscillation relatively to supporting frames 141 in the manner just described for supporting the slime table 114.

As shown in Fig. 11, the filter bed 120 has a bottom consisting of a screen 142 supported by an edge flange 120a extending inwardly from the

framework of the filter bed. The screen 142 supports a layer of filtering material 120d of for example, sponge rubber or other material adapted to engage and remove fine metallic particles from the slime, which filtering material is preferably held in place by a top screen 153, preferably provided with longitudinal ribs 154 holding it in flat condition. The filter bed 120 has hinged to its longitudinal upper edges at 120c, inturned flanges 120b to prevent the slime flowing over the edges 10 of the filter bed when the latter is reciprocated, which flanges are provided with horizontally extending projections as indicated, holding the edges of the screen 153 in place. The flanges 120b are held in place by latches 155 pivotally connected with the supporting rods 140 as indicated, so that moving the latches to their releasing position, permits the flanges 120b to be turned on their hinge connections 120c, when it is desired to remove the screens and the filter- 20 material from the filter bed.

The framework of the filter bed has secured thereto and extending below the filter bed, a pan 143 having imperforate side, end and bottom walls so that the pan may at all times be nearly 25 or quite full of water during the operation of the filter bed. The bottom wall of the pan 143 is shaped to form three parallel troughs 143a 143b, and 143c extending longitudinally of the filter bed and separated by upwardly extending 30 ridges 143d and 143e. The mid portion of the screen 142 is supported from the ridges 143d and 143e by a member 144 of triangular cross section engaging the screen 142 at its apex and resting at its lower edges on the ridges 143d and 143e, 35 webs 144a preferably joining the side walls of the member 144 at intervals to reinforce and strengthen it. As more clearly shown in Fig. 12, each of the side walls of the member 144 is preferably shaped so that it consists of a plurality 40 of shallow troughs 144b extending from the apex of said member to its lower edge, these troughs having slots 144c formed between them to permit the free flow of water through the member 144.

The rods 140 preferably extend around the 45 bottom of the pan 143 in the form of a web section as indicated at 140a, to fit and support the several troughs of the pan and thereby carry the pan and its contents for oscillation with the filter bed by the connecting rods 130.

The trough 144c has located therein, an imperforate tube 145 of soft rubber, connected by a flexible pipe or tube 146 with one end of a cylinder 147. The cylinder 147 contains a piston 148 secured to one end of a piston rod 149, the other end of which is pivotally connected with one end of a connecting rod 150, the other end of which engages a crank 151 carried by a shaft 152. The fluid medium contained in the rubber tube 145 and the corresponding end of the cylinder 147, is 55 preferably air or gas, although liquid, for example water, may be used if preferred. Rotation of the shaft 152, produces corresponding movement of the piston 148, which in turn moves the fluid in the cylinder alternately into and from the 60 tube 145, producing corresponding inflation and deflation thereof, at a rate determined by the rate of rotation of the shaft 152. Each inflation of the tube 145, indicated at 145a, displaces a corresponding amount of water from the trough 65 143c and through the slots 144c and correspondingly acts upon the filter material 120d to raise and loosen the small particles of solid material held by said filter material. In this manner, the material caught by the filter bed may be agitated 70 75

as desired, to loosen the solid particles adhering to the filter bed and facilitate its filtering action. The shallow grooves 144b of the member 144, serve to direct the fine solid material dropping 5 through the screen 142, into the trough 143a and 143b and prevent any appreciable amount of said solid material passing through the member 144 into engagement with the rubber tube 145. When the filter bed has been operated for a sufficient 10 length of time to collect an appreciable quantity of solid material in the troughs 143a and 143b, the filter material 120d may be removed from the filter bed, the screen 142 may then be removed, and access may be had to the troughs 15 143a and 143b for cleaning purposes. At the same time, the member 144 may be removed and the trough 143c may be cleaned, if sufficient of the solid material has entered the trough 143c to warrant it.

20 While I have shown my invention in the particular embodiment above described, it will be understood that I do not limit myself to this exact construction as I may employ equivalents known to the art at the time of the filing of this 25 application without departing from the scope of the appended claims.

What I claim is:

1. In a slime table construction, the combination of a base supported in inclined position 30 for alternate movement in opposite directions, a layer of covering material on said base inactive relatively to mercury, said covering material having first grooves therein extending in the direction of movement of said base, said covering 35 material having second grooves therein extending across said first grooves, partitions in said second grooves dividing said first grooves respectively into a plurality of short portions each, mercury in each of said groove portions, and means for 40 moving said base alternately in opposite directions.

2. In a slime table construction, the combination of a base supported in inclined position for alternate movement in opposite directions, a 45 layer of covering material on said base inactive relatively to mercury, said covering material having first grooves therein extending in the direction of movement of said base, said covering material having second grooves therein extending 50 across said first grooves, partitions in said second grooves dividing said first grooves respectively into a plurality of short portions each, mercury in each of said groove portions, and means for moving said base alternately in opposite directions, each of said first grooves having 55 a lower wall inclined upwardly and towards the upper edge of the base and an upper wall curved away from said lower wall to merge tangentially with the upper surface of said covering material.

60 3. In a slime table construction, the combination of a base supported in inclined position for alternate movement in opposite directions, a layer of covering material on said base inactive 65 relatively to mercury, said covering material having first grooves therein extending in the direction of movement of said base, said covering material having second grooves therein extending across said first grooves, partitions in said 70 second grooves dividing said first grooves respectively into a plurality of short portions each, mercury in each of said groove portions, and means for moving said base alternately in opposite directions, said partitions being a sliding fit 75 in said second grooves and having openings reg-

istering with said first grooves for one position of said partitions, said partition openings being covered by said covering material for another position of said partitions.

4. In a slime table construction, the combination of a base supported in inclined position for alternate movement in opposite directions, a 5 layer of covering material on said base inactive relatively to mercury, said covering material having first grooves therein extending in the direction of movement of said base, said covering material having second grooves therein extending across said first grooves, partitions in said second grooves dividing said first grooves respectively into a plurality of short portions each, 10 mercury in each of said groove portions, and means for moving said base alternately in opposite directions, said partitions being a sliding fit in said second grooves and having openings registering with said first grooves for one position 15 of said partitions, said partition openings being covered by said covering material for another position of said partitions, said partitions having holes therethrough for receiving a partition moving tool. 20

5. In a slime table construction, the combination of a base supported in inclined position for alternate movement in opposite directions, a layer of covering material on said base inactive 25 relatively to mercury, said covering material having first grooves therein extending in the direction of movement of said base, said covering material having second grooves therein extending across said first grooves, partitions in said second 30 grooves dividing said first grooves respectively 35 into a plurality of short portions each, mercury in each of said groove portions, and means for moving said base alternately in opposite directions, said partitions having on their upper edges 40 curved flanges extending over the adjacent portions of said first grooves.

6. In a slime table construction, the combination of a base supported in inclined position for alternate movement in opposite directions, a 45 layer of covering material on said base inactive relatively to mercury, said covering material having first grooves therein extending in the direction of movement of said base, said covering material having second grooves therein extending 50 across said first grooves, partitions in said second grooves dividing said first grooves respectively into a plurality of short portions each, mercury in each of said groove portions, and means for moving said base alternately in opposite directions, said second grooves being deeper 55 than said first grooves.

7. In a slime table construction, the combination of a base supported in inclined position for alternate movement in opposite directions, a layer 60 of covering material on said base inactive relatively to mercury, said covering material having first grooves therein extending in the direction of movement of said base, said covering material having second grooves therein extending across said first grooves, partitions in said second 65 grooves dividing said first grooves respectively into a plurality of short portions each, mercury in each of said groove portions, means for moving said base alternately in opposite directions, pairs of rods extending upwardly from said base, a yoke engaging the upper ends of each pair of 70 said rods and extending laterally of said base, an anti-friction bearing supporting each of said yokes, a shaft extending longitudinally of and 75

above said base supporting said bearings, and frames supporting said shaft.

8. In a slime table construction, the combination of a base supported in inclined position for alternate movement in opposite directions, a layer of covering material on said base inactive relatively to mercury, said covering material having first grooves therein extending in the direction of movement of said base, said covering material having second grooves therein extending across said first grooves, partitions in said second grooves dividing said first grooves respectively into a plurality of short portions each, mercury in each of said groove portions, means for moving said base alternately in opposite directions, pairs of rods extending upwardly from said base, a yoke engaging the upper ends of each pair of said rods and extending laterally of said base, an anti-friction bearing supporting each of said yokes, a shaft extending longitudinally of and above said base supporting said bearings, and frames supporting said shaft, said moving means comprising a rotary shaft, cranks carried by said shaft, and connecting rods connecting said cranks and said base.

9. In a slime table construction, the combination of a base, covering material on said base adapted to carry mercury for amalgamation treatment of slime flowing over said covering material, a second base, filtering material carried by said second base for receiving treated slime from said covering material, means for moving said bases alternately in opposite directions, each of said bases being rectangular and said second base being wider than said first named base, a trough for receiving slime from said covering material and delivering it on said filtering material and increasing in width towards said filtering material, and partitions in said trough diverging towards said filtering material to distribute the slime laterally over said filtering material.

10. In a slime table construction, the combination of a conical base supported for oscillatory movement about its axis, covering material on said base having circular grooves for holding mercury, said covering material having second grooves therein extending across said first grooves, and partitions in said second grooves dividing each of said circular grooves into a plurality of relatively short portions.

11. In a slime table construction, the combination of a conical base supported for oscillatory movement about its axis, covering material on said base having circular grooves for holding mercury, said covering material having second grooves therein extending across said first grooves, and partitions in said second grooves dividing each of said circular grooves into a plurality of relatively short portions, each of said circular grooves having a lower wall inclined upwardly and towards the upper edge of the base and an upper wall curved away from said lower wall to merge tangentially with the upper surface of said covering material.

12. In a slime table construction, the combination of a conical base supported for oscillatory movement about its axis, covering material on said base having circular grooves for holding mercury, said covering material having second grooves therein extending across said first grooves, and partitions in said second grooves dividing each of said circular grooves into a plurality of relatively short portions, said partitions being a sliding fit in said second grooves and having openings registering with said circular grooves for one

position of said partitions, said partition openings being covered by said covering material for another position of said partitions.

13. In a slime table construction, the combination of a conical base supported for oscillatory movement about its axis, covering material on said base having circular grooves for holding mercury, said covering material having second grooves therein extending across said first grooves, and partitions in said second grooves dividing each of said circular grooves into a plurality of relatively short portions, said partitions being a sliding fit in said second grooves and having openings registering with said circular grooves for one position of said partitions, said partition openings being covered by said covering material for another position of said partitions, said partitions having holes therethrough for receiving a partition moving tool.

14. In a slime table construction, the combination of a conical base supported for oscillatory movement about its axis, covering material on said base having circular grooves for holding mercury, said covering material having second grooves therein extending across said first grooves, and partitions in said second grooves dividing each of said circular grooves into a plurality of relatively short portions, said partitions having on their upper edges curved flanges extending over the adjacent portions of said circular grooves.

15. In a slime table construction, the combination of a conical base supported for oscillatory movement about its axis, covering material on said base having circular grooves for holding mercury, said covering material having second grooves therein extending across said first grooves, and partitions in said second grooves dividing each of said circular grooves into a plurality of relatively short portions, said second grooves being deeper than said circular grooves.

16. In a slime table construction, the combination of a conical base supported for oscillatory movement about its axis, covering material on said base having circular grooves for holding mercury, said covering material having second grooves therein extending across said first grooves, partitions in said second grooves dividing each of said circular grooves into a plurality of relatively short portions, a fine-mesh screen above said covering material, and means for delivering slimes upon the upper portion of said screen.

17. In a slime table construction, the combination of a conical base supported for oscillatory movement about its axis, covering material on said base having circular grooves for holding mercury, said covering material having second grooves therein extending across said first grooves, partitions in said second grooves dividing each of said circular grooves into a plurality of relatively short portions, a fine-mesh screen above said covering material, a coarser-mesh screen above said fine-mesh screen, means for delivering slimes upon the upper portion of said coarser-mesh screen, and a filter bed carried by the lower portion of said base below the path of flow of material on said coarser-mesh screen and receiving material discharged from the lower portion of said fine-mesh screen and from the lower portion of said covering material.

18. In a slime table construction, the combination of a conical base supported for oscillatory movement about its axis, covering material on said base having circular grooves for holding mercury, said covering material having second

grooves therein extending across said first grooves, partitions in said second grooves dividing each of said circular grooves into a plurality of relatively short portions, a fine-mesh screen above said covering material, a coarser-mesh screen above said fine-mesh screen, means for delivering slimes upon the upper portion of said coarser-mesh screen, a filter bed carried by the lower portion of said base below the path of flow 10 of material on said coarser-mesh screen and receiving material discharged from the lower portion of said fine-mesh screen and from the lower portion of said covering material, said coarser-mesh screen extending from over the upper portion 15 of said base part way towards the lower portion of said base, and an imperforate shield extending from the lower edge of said coarser-mesh screen and continuing the path of flow of material from the latter over and outside of said filter bed.

19. In a slime table construction, the combination of a conical base supported for oscillatory movement about its axis, covering material on said base having circular grooves for holding 25 mercury, said covering material having second grooves therein extending across said first grooves, partitions in said second grooves dividing each of said circular grooves into a plurality of relatively short portions, said covering material 30 being in sections permitting ready handling, and a flange extending upwardly from the lower portion of said base holding said covering sections in place.

20. In a slime table construction, the combination of a conical base supported for oscillatory movement about its axis, covering material on said base having circular grooves for holding mercury, said covering material having second grooves therein extending across said first 40 grooves, partitions in said second grooves dividing each of said circular grooves into a plurality of relatively short portions, a screen above said covering material, said base, said covering material and said screen having central clearance openings, a pipe extending vertically through said 45 openings, a universal joint supporting said pipe restraining said pipe from rotary movement about its axis and permitting a wobbling movement of said pipe, devices closing the lower end of said pipe, means for supplying slimes to said pipe, said pipe having an enlarged rim at its upper end for directing overflow from said pipe upon said screen, and mechanism for oscillating said base and for wobbling said pipe at a slower rate than 50 the rate of oscillation of said base.

21. In a slime table construction, the combination of a conical base supported for oscillatory movement about its axis, covering material on said base having circular grooves for holding mercury, said covering material having second 55 grooves therein extending across said first grooves, partitions in said second grooves dividing each of said circular grooves into a plurality of relatively short portions, a screen above said covering material, said base, said covering material and said screen having central clearance openings, a pipe extending vertically through said 60 openings, a universal joint supporting said pipe restraining said pipe from rotary movement about its axis and permitting a wobbling movement of said pipe, devices closing the lower end of said pipe, means for supplying slimes to said pipe, said pipe having an enlarged rim at its upper end for directing overflow from said pipe upon said screen, mechanism for oscillating said 65

base and for wobbling said pipe at a slower rate than the rate of oscillation of said base, and a shield surrounding and spaced from said rim and directing overflow therefrom.

22. In a slime table construction, the combination of a conical base supported for oscillatory movement about its axis, covering material on said base having circular grooves for holding mercury, said covering material having second 10 grooves therein extending across said first 15 grooves, partitions in said second grooves dividing each of said circular grooves into a plurality of relatively short portions, a screen above said covering material, said base, said covering material and said screen having central clearance 20 openings, a pipe extending vertically through said openings, a universal joint supporting said pipe restraining said pipe from rotary movement about its axis and permitting a wobbling movement of said pipe, devices closing the lower end 25 of said pipe, means for supplying slimes to said pipe, said pipe having an enlarged rim at its upper end for directing overflow from said pipe upon said screen, mechanism for oscillating said base and for wobbling said pipe at a slower rate 30 than the rate of oscillation of said base, said slime supplying means comprising a flexible tube inserted in the upper end of said pipe, and a second flexible tube extending into the upper end of said pipe for supplying water thereto.

23. In a slime table construction, the combination of a conical base supported for oscillatory movement about its axis, covering material on said base having circular grooves for holding mercury, said covering material having second 35 grooves therein extending across said first grooves, partitions in said second grooves dividing each of said circular grooves into a plurality of relatively short portions, a screen above said covering material, said base, said covering material and said screen having central clearance 40 openings, a pipe extending vertically through said openings, a universal joint supporting said pipe restraining said pipe from rotary movement about its axis and permitting a wobbling movement 45 of said pipe, devices closing the lower end of said pipe, means for supplying slimes to said pipe, said pipe having an enlarged rim at its upper end for directing overflow from said pipe upon said screen, a first gear for wobbling said 50 pipe, a smaller gear meshing with said first gear, and devices connected with said smaller gear for oscillating said base, said first gear having an eccentric opening through it receiving the lower portion of said pipe to move it.

24. In a slime table construction, the combination of a conical base supported for oscillatory movement about its axis, covering material on said base having circular grooves for holding mercury, said covering material having second 60 grooves therein extending across said first grooves, partitions in said second grooves dividing each of said circular grooves into a plurality of relatively short portions, a screen above said covering material, said base, said covering material and said screen having central clearance 65 openings, a pipe extending vertically through said openings, a universal joint supporting said pipe restraining said pipe from rotary movement about its axis and permitting a wobbling movement 70 of said pipe, devices closing the lower end of said pipe, means for supplying slimes to said pipe, said pipe having an enlarged rim at its upper end for directing overflow from said pipe upon said screen, a first gear for wobbling said 75

pipe, a smaller gear meshing with said first gear, devices connected with said smaller gear for oscillating said base, said first gear having a slot extending radially through it, a plate pivotally mounted on said gear and having a slot extending obliquely across said gear slot, and devices for holding said plate in desired position on said first gear, said slots being of substantially the same width and receiving the lower portion of said pipe.

25. In a slime table construction, the combination of a conical base supported for oscillatory movement about its axis, covering material on said base having circular grooves for holding mercury, said covering material having second grooves therein extending across said first grooves, partitions in said second grooves dividing each of said circular grooves into a plurality of relatively short portions, a screen above said covering material, said base, said covering material and said screen having central clearance openings, a pipe extending vertically through said openings, a universal joint supporting said pipe restraining said pipe from rotary movement about its axis and permitting a wobbling movement of said pipe, devices closing the lower end of said pipe, means for supplying slimes to said pipe, said pipe having an enlarged rim at its upper end for directing overflow from said pipe upon said screen, mechanism for oscillating said base and for wobbling said pipe at a slower rate than the rate of oscillation of said base, and a

shield carried by said pipe above and around said universal joint protecting the latter from said slimes.

26. In a slime table construction, the combination of a conical base supported for oscillatory movement about its axis, covering material on said base having circular grooves for holding mercury, said covering material having second grooves therein extending across said first grooves, partitions in said second grooves dividing each of said circular grooves into a plurality of relatively short portions, a screen above said covering material, said base, said covering material and said screen having central clearance openings, a pipe extending vertically through said openings, a universal joint supporting said pipe restraining said pipe from rotary movement about its axis and permitting a wobbling movement of said pipe, devices closing the lower end of said pipe, means for supplying slimes to said pipe, said pipe having an enlarged rim at its upper end for directing overflow from said pipe upon said screen, mechanism for oscillating said base and for wobbling said pipe at a slower rate than the rate of oscillation of said base, said closing devices comprising a valve having a projecting arm and means tending to hold said valve in closed position, and a member engaging said valve arm during movement of said pipe to periodically open said valve.
